UNITED STATES PATENT OFFICE.

ARTHUR A. FRANK, OF MILWAUKEE, WISCONSIN, ASSIGNOR TO THE FISK RUBBER COMPANY, OF CHICOPEE FALLS, MASSACHUSETTS, A CORPORATION OF MASSACHUSETTS.

CALENDERING.

Application filed May 15, 1922. Serial No. 561,103.

It is well known that normal deterioration in the textile content of fabric tires is largely due to the friction between the weft threads and that this cause of deterioration 5 may be decreased by using so-called cord fabric (fabric having but very light weft threads) and eliminated by employing a textile content having no weft threads whatsoever. In forming tires of such a textile 10 content it is still convenient to use the textile content in the form of strips of rubberized textile material and accordingly convenience in building requires the development of a method of rubberizing a 15 sheet of separate cords. My invention relates to such rubberizing. In the drawings accompanying this specification and forming a part thereof I have shown, for purposes of illustration, one form which my invention may assume. In these drawings:

Figure 1 is a vertical cross section through a calender constructed in accordance with my invention,

Figure 2 is a section on the line 2—2 of 25 Figure 1, while

Figure 3 is a section on the line 3—3 of Figure 1.

The calender 11 herein shown comprises a frame 12, upper roll 13, center roll 14, and 30 lower roll 15. The rubber is fed into the bight of the rolls 13 and 14 to form the bank 16 and be sheeted out onto the roller 14 as a sheet 17 which is carried by the roller 14 into the bight of the rollers 14 and 15 where it joins the sheet 18 of individual unrubberized cords and with it forms the sheet 19 of united rubberized cords.

In such a process considerable pressure is imposed upon the sheets 17 and 18 as they 40 pass between the rollers 14 and 15 and this pressure tends to force apart the cords of the sheet 18 to thus reduce the number of cords per unit of width. I find that this action may be overcome by laterally supporting the cords as they pass between the rolls 14 and 15 and that the cords may be conveniently supported by grooving one of the rolls 14 and 15, preferably the roll 15 45 which is in direct contact with the sheet 18.

In the drawings I have shown the roll 15 as 50 provided with a groove 20 for each cord of the sheet 18 and the calender 11 as provided with a bar 21 which acts to press the sheet 18 into engagement with the roll 15 to cause each cord of the sheet 18 to enter one of the 55 grooves in the roll 15 as shown in Figure 2 so that the cords will be held in position when the pressure is applied, as shown in Figure 3. In this manner the sheet 18 may be satisfactorily calendered to form the rubberized sheet 19 which may be further rubberized as desired.

The disclosure herein covers one embodiment of my invention. It is, however, illustrative only and my invention is not limited thereto.

I claim:

1. A calender for rubberizing a sheet of cords, comprising, a pair of rolls adapted to form a sheet of rubber upon one roll of the 70 pair, a third calender roll positioned in calendering relation to the latter roll and provided with means for laterally supporting the cords as the cord sheet is subjected to pressure between the last named rolls to rubberize the sheet of cords.

2. A calender for rubberizing a sheet of cords, comprising, a pair of rolls adapted to form a sheet of rubber upon one roll of the 80 pair, a third calender roll positioned in calendering relation to the latter roll and provided with grooves for laterally supporting the individual cords as the cord sheet is subjected to pressure between the last named rolls to rubberize the sheet of cords.

3. A calender for rubberizing a sheet of cords, comprising, a pair of rolls adapted to form a sheet of rubber upon one roll of the 90 pair, a third calender roll positioned in calendering relation to the latter roll and having grooves formed in its surface adapted to position and laterally support the individual cords as the cord sheet is subjected to pressure between the last named rolls to rubberize the cord sheet.

In testimony whereof I have signed my name to the above specification.

ARTHUR A. FRANK.
